Primary Examiner — Janice Hallmark*(74) Attorney, Agent, or Firm* — Harness, Dickey &
Pierce, P.L.C.(57) **CLAIM**

The ornamental design for a smoking article, as shown and
described.

DESCRIPTION

FIG. 1 is a perspective view of a smoking article showing
our new design.

FIG. 2 is a side elevational view thereof; and,

FIG. 3 is a right end elevational view thereof.

Broken lines illustrate portions of the smoking article that
form no part of the claimed design.
